ELECTRIC RANGE

Arthur N. Bec Var and Edward W. Harrison, Jefferson County, Ky., assignors to General Electric Company, a corporation of New York

Application March 21, 1957, Serial No. 45,378

Term of patent 14 years

(Cl. D81—4)

FIG. 1.

FIG. 2.

FIG. 3.

FIG. 4.

Fig. 1 is a perspective view of an electric range embodying our design.

Fig. 2 is a fragrant cross sectional view taken along the lines 2—2 of Fig. 1.

Fig. 3 is a fragrant cross sectional view taken along the line 3—3 in Fig. 1.

Fig. 4 is a fragrant cross sectional view taken along the line 4—4 in Fig. 1.

The dominant features of our design reside in the portions shown in full lines.

We claim:

The ornamental design for an electric range, as shown and described.
